UNITED STATES PATENT OFFICE.

PETER J. GRUEBEL, OF BROOKLYN, NEW YORK.

AIRPLANE.

Application filed March 2, 1925. Serial No. 12,605.

To all whom it may concern:

Be it known that I, PETER J. GRUEBEL, a citizen of the United States, residing at Brooklyn, in the county of Kings and State 5 of New York, have invented certain new and useful Improvements in Airplanes, of which the following is a specification.

The invention relates to improvements in airplanes, and is more particularly adapted 10 to airplanes of the biplane type. It has for its object to facilitate landings and to provide for an emergency control whereby the plane may be caused to descend substantially vertically and at a safe velocity. A 15 further object of the invention consists in a construction of plane such that when the plane is not in use the same may have its principal dimension disposed vertically, thus enabling a greater number of planes to 20 be accommodated over a given surface than is now possible.

To this end, the invention consists in so associating the oppositely disposed wings of an airplane with the body thereof that the 25 said wings may be released and swung at will into a substantially vertical plane while simultaneously therewith conical or tent shaped supporting surfaces carried by the wings are caused to be spread to afford 30 sufficient sustaining area, as in the case of a parachute, to permit a substantially vertically descent of the plane as a whole and at a not dangerous velocity.

The nature of the invention, however, will 35 best be understood when described in connection with the accompanying drawings, in which—

Fig. 1 is a plan of the novel plane, with the covering of one of the wings removed.

Fig. 2 is a plan view of the plane collapsed for vertical descent.

Fig. 3 is a fragmentary side view of the plane.

Fig. 4 is a rear view of the plane, one of 45 the wings being shown in section, and both wings also being indicated in dotted lines in their vertically disposed positions with sustaining surfaces for vertical descent extended.

Fig. 5 is an underneath view of one of the wings and portion of the body of the plane.

Figs. 6 and 7 are enlarged transverse sections taken respectively on the lines 6—6 and 7—7, Fig. 5.

Fig. 8 is a detail plan view of the releasing gear, and Fig. 9 is a further and frag-

mentary detail view of portions of the releasing gear.

Fig. 10 is a detail perspective view of the control member of the releasing gear.

Fig. 11 is a fragmentary detail sectional view of the sustaining surface extending means.

Fig. 12 is a perspective view of a sustaining member, and Fig. 13 is a perspective 35 view of the same in its extended condition, as for vertical descent.

Referring to the drawings 20 designates the body of an airplane, which is herein shown as of the biplane type, having extending laterally therefrom in opposite directions wings 21 composed of upper and lower frames 23 and 24 respectively, supported and maintained in their relative position by a suitable fuselage including a plurality of vertically disposed posts 25. In accordance with the present invention, these posts are made hollow for the purpose hereinafter set forth. The upper frames are covered in the usual manner with fabric or other suitable material to afford the necessary wing spread, while the covering of wing spread of the lower plane is made in two folds 26 and 27, Fig. 12, arranged to be separated or distended in manner hereinafter set forth to afford a conical or tent-shaped sustaining member as shown more particularly in Fig. 13. Normally, however, the two folds are together forming a flat wing spread in the usual manner.

In accordance with the invention, furthermore, the said wings 21 are not to be rigidly secured to the body 20 as is the usual practice, but are arranged to have a hinged connection therewith at the upper frames, as thru suitable universal joints 28. The arrangement is such that, when desired, the said wings may swing upwardly, hinging about the body 20 or rather the universal joints 28 secured thereto.

If the wings be then maintained in this position, the plane will assume a shape substantially as shown in Fig. 2 of the drawings and occupy considerably less superficial area than when in the operative position shown in Fig. 1. Thus, a greater number of planes may be stored in a given area when the same are not in use.

Normally, and when the plane is in use, the said wings will maintain their generally horizontal position as shown in Figs. 1 and 4, as the upright position thereof,

indicated in dotted lines, Fig. 4, is employed only in landing or in an emergency for the purpose of permitting descent of the plane in a substantially vertical direction, 5 the velocity of descent being predetermined by the spread of the pair of parachute-like members or tent-shaped sustaining surfaces developing automatically from the lower wing spread simultaneously with the shifting of the wings from a horizontal to a vertical position.

To this end, the lower wing spread though separable is normally maintained against separation from the bottom frame 15 member by a supplementary frame member 30 along its under surface, said supplementary frame member being hinged at its outer end to a said lower frame member and holding the folds 26 and 27 between it- 20 self and the plane frame member. The said supplementary frame member is, furthermore, connected to a series of rods 31, one or more of which may be jointed intermediate its ends if necessary; and these rods 25 at their inner ends are secured to sprung-urged plungers mounted to reciprocate in the hollow posts 25 of the fuselage. The arrangement is such that the plungers are urged outwardly by the springs and to 30 swing the lowermost or supplementary frame and carry with the same one of the folds which is attached to said supplementary frame. The other fold is attached to bars 32 hingedly connected to the frame 24 35 and having channel-shaped ends 33 slidable upon the posts 25 and overhanging also the side of the said lower frame 24 and provided with perforations 34 in the overhanging portions. With the outer of the two 40 folds extended by the frame 30 and permitting thus the air to get underneath the same, the other fold will likewise be forced inwardly toward the wing frame 23, the ends 33 sliding along the respective posts 25 the 45 proper extent and thus providing two tent-shaped sustaining members above and at either side of the body 20 of the plane, as clearly indicated in Fig. 4, in dotted lines. This will provide ample sustaining surface 50 to bring the plane down gradually in a substantially vertical direction; and in order to fly the same again it will, of course, be necessary to secure the wings in their normal horizontal position.

55 This and the release of the wings for descent purposes may conveniently be effected thru the medium of locking rods 35 carrying plates 36 each of which is provided with a pair of cam grooves 37. Into the latter are adapted to fit pins 38 extending from and at right angles to pairs of rods 39 which are aligned with the openings 34 of the ends 33 and also with registering openings 40 thru the sides of the frame 24. 60 65 When the ends of the respective pair of

rods are thus passed thru the frame and the end pieces 33, the same will be securely held to the lower frame of a wing and contain between same the lower wing surfaces in folded position so that the plane is substantially similar to the usual well-known types. When, however, it is desired to release the supplementary frame as well as the wings themselves, the rod 35 is arranged to be axially moved and will thus shift the cam plates to draw inwardly the corresponding pairs of rods and release thereby the said supplementary frame and angle pieces, as indicated. To assist in this action, the rod is spring-drawn outwardly as by means of a spring 45; and at its inner end, said rod is further provided with an upturned portion or detent 46 which is normally held by a rotatable block 47 against such axial movement. However, when a lever 48, pivotally mounted in the body 20, is rocked, the block 47 is withdrawn from its engagement with the detent 46 and the rod drawn axially by the spring 45 to effect the movements aforesaid. The operation is duplicated for the opposite wing of the plane, and the respective blocks pass thru slots 49 in the frame 24 to permit the same to swing upwardly.

I claim:—

1. An airplane having a body and horizontally disposed wings extending in opposite directions therefrom, means to hingedly secure the wings to the body, means to normally retain said wings in fixed relation to the body, means for releasing said wings to permit the same to swing into a plane at right angles to their normal position, sustaining members carried by the respective wings, and means to automatically open up the same upon release of said wings.

2. An airplane having a body and horizontally disposed wings extending in opposite directions therefrom, means to hingedly secure the wings to the body, means to normally retain said wings in fixed relation to the body, means for releasing said wings to permit the same to swing into a plane at right angles to their normal position, tent-shaped sustaining members carried by the respective wings, and means to automatically open up the same upon release of said wings.

3. An airplane having a body and horizontally disposed wings extending in opposite directions therefrom, means to hingedly secure the wings to the body, means to normally retain said wings in fixed relation to the body, means for releasing said wings to permit the same to swing into a plane at right angles to their normal position, and sustaining surfaces normally forming the wing spread of said wings and comprising suitable fabric layers folded upon each other and adapted to be distended to provide a tent-shaped member for sustaining the

plane in a vertical position when the said wings are released.

4. An airplane having a body and horizontally disposed wings extending in opposite directions therefrom, universal joints connecting said wings with said body to permit the former to swing at right angles to the latter, means to normally retain said wings in fixed relation to the body, a releasing lever to disengage the said retaining means, sustaining members, and means actuated by said releasing lever to also release said sustaining members.

5. An airplane having a body and horizontally disposed wings extending in opposite directions therefrom, universal joints connecting said wings with said body to permit the former to swing at right angles to the latter, means to normally retain said wings in fixed relation to the body, a releasing lever to disengage the said retaining means, separable sustaining members, and means actuated by said releasing lever to also release said sustaining members and including means to project outwardly the walls of the separable sustaining members.

6. An airplane having a body and horizontally disposed wings extending in opposite directions therefrom, universal joints

connecting said wings with said body to permit the former to swing at right angles to the latter, means to normally retain said wings in fixed relation to the body, and a releasing lever to disengage the said retaining means, separable sustaining members, and means actuated by said releasing lever to also release said sustaining members and including means to project outwardly the walls of the separable sustaining members, said means comprising hollow frame posts of the fuselage of the plane, and sprung plunger movable therein and in connection with the sustaining members.

7. An airplane having a body and horizontally disposed wings extending in opposite direction therefrom, means to hingedly secure the wings to the body, means to normally retain said wings in fixed relation to the body, means for releasing said wings to permit the same to swing into a plane at right angles to their normal position, a supplementary frame hingedly secured to each of the wings and carrying respective sustaining members, and means to release the respective supplementary frames upon release of the said wings.

In testimony whereof I affix my signature.

PETER J. GRUEBEL.
